GUIDE CLIP FOR REPAIRING
COMMUTATORS

George W. Dinkler, Beckley, W. Va.

Application September 5, 1947, Serial No. 772,368

3 Claims. (Cl. 29—67)

1

This invention relates to dressing tools for the commutators of electrical machines and more particularly to a guide clip adapted to be employed in undercutting the strip insulation between adjacent commutator segments.

A main object of the invention is to provide a novel and improved guide clip to be employed in dressing commutators, said clip being very simple in structure, easy to apply and providing an efficient means for guiding an undercutting tool between adjacent commutator segments without risk of injury to said segments.

A further object of the invention is to provide a readily attachable guide clip for undercutting the insulation strips between commutator segments during the dressing of a commutator, said clip being inexpensive to manufacture, sturdy in construction and effectively protecting the commutator segments against damage by the undercutting tool.

Further objects and advantages of the invention will become apparent from the following description and claims, and from the accompanying drawings, wherein:

Figure 1 is a perspective view of a guide clip constructed in accordance with the present invention.

Figure 2 is an end elevational view of an electrical machine showing the guide clip of Figure 1 engaged with the commutator thereof.

Figure 3 is a top plan view of the commutator portion of the machine of Figure 2 showing the guide clip mounted thereon.

Referring to the drawings, 11 designates the guide clip generally, said clip being formed of suitable resilient metal strip material, such as spring steel, and being formed to define a top arm 12 and a lower arm 13 connected by a curved bend 14. Secured to or formed integrally with the end of top arm 12 is a bar member 15 extending transversely of and being substantially flush with said top arm 12. The rearward portion 16 of bar member 15 is bent upwardly at right angles to the intermediate portion of said bar member and the forward portion 17 thereof is bent downwardly at right angles to said intermediate portion. The bar member 15 is formed with a slot 18 which extends for the major portion of the length of the bar member, including the angled bent portions 16 and 17.

The lower arm 13 is substantially longer than the upper arm 12 and is provided with a well member extending from its end, the member being formed with a V-bend 19 substantially in vertical alignment with the bar member 15. The

2

bottom apex of the V-bend 19 is likewise in vertical alignment with the slot 18. The outer end of said lower arm 13 extends beyond the V-bend 19 to define a horizontal finger tab 20.

5 In using the device, the arms 12 and 13 are engaged around a commutator, such as shown at 21, in the manner illustrated in Figure 2, the V-bend 19 receiving the bottom of the commutator and the slotted bar member 15 engaging the top thereof with spring pressure. The clip is then rotated until the insulation strip between a pair of adjacent commutator segments is in alignment with the slot 18. The cutting tool, such as a hacksaw blade, is inserted in said slot, the tool projecting 15 through the slot portion in upwardly bent bar element 16 and engaging the insulating strip through the remaining slot portions. The insulation strip may then be undercut as desired by endwise movement of the cutting tool. The slot 20 18 in the bar member 15 protects the adjacent commutator segments against damage by the cutting tool.

When the undercutting operation has been completed on one insulation strip, the guide clip 25 is rotated until the next strip is in alignment with the slot 18 and the process is repeated.

The depending bar element 17 is positioned in abutment with the end surface 22 of the commutator so as to positively locate the guide clip 30 in a fixed transverse plane with respect to the axis of the commutator during each insulation strip undercutting operation. This provides uniform tool guiding conditions for the undercutting of all insulation strips on the commutator.

35 By the use of a tool guide clip as above described, the time required to repair commutators, such as the commutators of automobile generators, starting motors and the like, is materially reduced.

40 While a specific embodiment of a commutator repair guide clip has been disclosed in the foregoing description it will be understood that various modifications within the spirit of the invention may occur to those skilled in the art. Therefore, it is intended that no limitations be placed 45 on the invention except as defined by the scope of the appended claims.

What is claimed is:

1. A guide clip of the character described, 50 comprising a U-shaped resilient strip member having substantially parallel upper and lower arms, the upper arm carrying at its end a transversely extending slotted bar element having an upwardly-projecting rear portion and having a 55 downwardly projecting forward portion, the slot

extending into said rear and forward portions, and the lower arm being formed with a concave portion substantially vertically aligned with said slotted bar element.

2. A guide clip of the character described, comprising a U-shaped resilient strip member having substantially parallel upper and lower arms, the upper arm carrying at its end a transversely extending bar element formed with a slot and projecting upwardly at a right angle at its rear portion and projecting downwardly at a right angle at its forward portion, the slot extending through the major portion of the length of said bar element and being included in said upwardly and downwardly projecting rear and forward portions, and the lower arm being formed with a V-bend substantially vertically aligned with said bar element.

3. A guide clip of the character described comprising a U-shaped resilient strip member hav- 20

ing substantially parallel upper and lower arms, a slotted bar element positioned transversely of said upper arm adjacent its free end and secured thereto adapted to slidably receive a cutting tool, and a well member projecting from the free end of said lower arm, said well member being in alignment with said slotted bar element.
